UNITED STATES PATENT OFFICE.

ALFRED WILLIAM SMITH, OF VICTORIA, LONDON, ENGLAND.

MACHINE FOR SETTING AND STROPPING RAZOR-BLADES.

1,231,802.

Specification of Letters Patent.

Patented July 3, 1917.

Application filed October 23, 1916. Serial No. 127,137.

To all whom it may concern:

Be it known that I, ALFRED WILLIAM SMITH, subject of the King of Great Britain and Ireland, residing at 4 Moreton Terrace Mews, Victoria, in the county of London, England, have invented certain new and useful Improvements in Machines for Setting and Stropping Razor-Blades, of which the following is a specification.

10 My invention relates to an improved machine or device for grinding, setting, and stropping the blades of safety and other razors, and for brevity will be referred to in this specification and in the claims appended thereto as a "stropping machine."

15 The object of the invention is to provide a machine which will satisfactorily perform all the operations necessary in grinding, setting and stropping a razor blade and 20 which shall also be simple and inexpensive in construction. One construction of machine will be fully described and the novel features thereof pointed out in the claims. In the accompanying drawings which illustrate this construction:—

25 Figure 1 is a front elevation.

Fig. 2 is a plan.

Fig. 3 is an elevation showing a section on the line A—B of Fig. 2.

30 Fig. 4 is a side elevation showing a section on the center line of Fig. 1 but with the operating or driving band omitted.

Fig. 5 is a sectional view of a blade holder, and

35 Fig. 6 is another view of a blade holder showing the parts thereof separated.

The machine comprises a frame 1 which is preferably stamped out of sheet metal and of a cross or diamond shape. Near the 40 upper extremity of the frame there is provided an aperture 2 conveniently of a key-hole shape so that the frame can be suspended from a nail or other projection. At or near the extremities of the horizontal 45 part of the frame there are mounted two spindles or rods 3, 4 which extend through the frame and are secured by nuts 5, 6 respectively screwed on to them. These rods 3, 4 constitute the supports for two blade

50 holders hereinafter to be described.

The outer or front ends of these fixed rods pass through a cross-bar 7 which is secured on them by suitable milled nuts 8, 9 respectively, it is also provided near the 55 center with a hole or bearing to receive a

spindle 10 which is secured to the frame 1 at its other end by a nut 11. This spindle or rod 10 constitutes a fixed support upon which a drum 12 rotates, and this drum carries the stropping or grinding medium 13. 60 A plurality of such drums may be provided with the machine having a variety of operative surfaces to perform any series of sharpening operations on the blades. It will be seen that by unscrewing the milled 65 nuts 8, 9, the cross-bar 7 can be removed and then the drum 12 can be freely slid off its spindle 10 and another one substituted for it.

The blade-holders which are shown on the 70 machine in Fig. 2 and in detail in Figs. 5 and 6 comprise suitable stamped clips 14 bent at one edge 15 to encircle one of the spindles 3, 4. Positioning pins 16 or other suitable means are provided on the clip 14 75 to engage with apertures or other means on the blade 18. The two ends of the clip 14 are provided with lugs 17 bent over to face the surface of the clip, and a spring clip 19 is arranged to slide under these lugs 80 and press on the razor blade 18. The rear edge of this member is bent over as at 20 to embrace the part 15 of the member 14 and is extended to provide a suitable finger grip for withdrawing the slide 19 from 85 its engaged position. The opposite edge of the plate 19 is slotted at 21 to accommodate the pins 16, when it is pushed home. These blade holders are mounted, as stated above, on the fixed rods 3, 4 and are 90 so designed that the edge of a blade in them can be tangential to and in contact with the abrasive or stropping surface of the drum 12 in either of two positions as shown in Fig. 1, so that the motion of the 95 roller or drum 12 is in a direction away from the edge of the blade so that the latter cannot catch in the surface of the roller to do any damage.

The drum 12 is turned down at one end 100 22 and provided with a groove 23 constituting a pulley for a cord or other suitable driving member 24. Each of the blade holders 14 has a pulley 25 secured on the end of the part 15 concentrically with the spindle 3 or 105 4 on which the holder is mounted and these pulleys may be grooved as shown in Fig. 2 if so desired.

The driving cord 24 is so arranged that it completely encircles the pulley 22, 23, and 110

partially encircles the pulleys 25 as shown in Fig. 3. The ends of the cord are led downward through guides at the bottom of the frame as also shown in this figure and are 5 provided with rings, loops or other convenient means for grasping them in the hands. The guides are conveniently formed of sleeves 26 loosely mounted on pins 27 secured in the frame 1 and connected by a 10 bridge-piece 28 to stiffen and support them.

When blades to be treated have been secured in the two holders, the machine is operated by grasping the ends of the cord 24 one in each hand and imparting a reciprocating 15 motion to it.

Referring to Figs. 1 and 3, if the right-hand cord is pulled downward the pulleys 25 will both be rotated in a counter-clockwise direction, thereby lifting the blades off the 20 drum 12 and carrying them around till they engage it again on the other side of their respective spindles 3, 4. Also the drum 12 will be set in rotation in a counter-clockwise direction, so that when the blades are in contact 25 with it the drum rotates away from the edge of the blades. Similarly when the cord 24 is moved in the opposite direction the various parts are readjusted so that the opposite sides of the blades are held in contact 30 with the roller 12 which again rotates away from the edges being treated.

It is an important feature of this invention that the pulleys 25 should be smaller than the pulley 22, 23, in order that their rotation 35 may be more rapid and lift the blades clear of the drum 12 before it is started in movement in a reverse direction. It will be apparent that when a blade holder has been rotated sufficiently to bring its blade into 40 contact with the drum 12, no further rotation is possible and the cord therefore slips over the pulleys 25 during the continuing movement of the drum. The frictional drag of the cord however on these pulleys causes 45 the blades to be pressed on the stropping surface with the requisite pressure for operating on them.

Another feature of the machine consists in the means for imparting a slight axial or 50 endwise movement to the drum 12 during its rotation. This is effected by forming a suitable screw-thread 36 on the spindle 10 as shown in Fig. 4. The drum 12 is threaded internally or has a nut mounted in it to cooperate 55 with this screw so that when it is rotated by means of the cord it is also caused to travel axially. This movement compensates for any irregularities on the surface of the drum and produces a finer or keener 60 edge on the blades than could otherwise be obtained. In order to permit the cord 24 to remain in proper engagement with the pulleys 25 in any axial position of the drum it may be necessary to make these pulleys 65 cylindrical, without any groove, or with a

wide groove, so that the cord can travel along them with the change in position of the groove 23 of the pulley 22.

In order to prevent the end face of the stropping drum 12 and also the end face of 70 the pulley 22 from jamming or retaining any appreciable frictional grip either upon the cross bar 7 or the frame 1 when the drum 12 is at either end of its axial traverse, a projection 29 is formed both upon the end of the 75 drum and the pulley or washers may be mounted upon the spindle 10 in equivalent positions. These projections are preferably made slightly convex so as to reduce the jamming or screwing action referred to above, 80 to a minimum, and permitting the direction of rotation of the drum to be easily reversed. It will be appreciated that one of these projections 29 also acts to prevent the edge of the stropping surface 13 from fouling the 85 cross bar 7.

It will be appreciated that various modifications may be made in the precise details of construction of this machine without departing from the scope of the present invention, and that while this machine can be adapted by the provision of suitable blade 90 holders for treating any type of safety or other razor blade, it is particularly suitable for use in grinding and stropping safety 95 razor blades of the "Gillette" type.

What I claim as my invention and desire to secure by Letters Patent is:—

1. In a machine for grinding and stropping razor blades the combination of, a rotatable drum, a plurality of rotatable blade-holders, spindles whereon said blade-holders are mounted arranged in a circle concentric with said drum and parallel with the axis thereof, a pulley rotatively engaging said 100 drum, a plurality of smaller pulleys each rotatively engaged with one of said blade-holders and a reciprocatable cord engaging all of said pulleys.

2. In a machine for grinding and stropping razor blades the combination of, a rotatable drum, a grooved pulley secured thereto concentric with the axis of rotation thereof, a plurality of rotatably mounted blade-holders, a plurality of pulleys each of 115 smaller diameter and greater axial length than said grooved pulley and each secured to a rotatable blade-holder and a reciprocatable driving belt engaging all of said pulleys.

3. In a machine for grinding and stropping razor blades the combination of, a frame, a spindle secured thereto, a drum rotatably mounted on said spindle, a plurality of spindles also mounted on said frame 125 and arranged on a circle concentric with said first-mentioned spindle, a retaining member engaging the ends of all of said spindles, detachable means for securing it on some of them, blade-holders mounted on 130

said plurality of spindles, a pulley on said drum, a smaller pulley on each of said blade-holders and a reciprocatable flexible driving band engaging all of said pulleys.

- 5 4. In a machine for grinding and stropping razor blades the combination of, a screw-threaded spindle, a drum rotatably mounted on said spindle and threaded internally to engage said spindle, a plurality 10 of rotatable blade-holders, means for rotating said drum and simultaneously rotating said blade-holders at a higher speed, and a frame member engaging the end of said spindle to limit the axial movement of said 15 drum.
5. In a machine for grinding and stropping razor blades the combination of a screwed spindle, an internally screwed drum rotatable on said spindle, frame-members 20 each engaging one end of said spindle, a dis-

tance piece of smaller diameter than said drum at each end thereof between it and said frame-members, rotatable blade-holders, a pulley on said drum, a smaller pulley on each of said blade-holders and means for 25 rotating said pulleys alternately in opposite directions.

6. In a machine for grinding and stropping razor blades the combination of, a spindle, a drum rotatable and axially movable thereon, a convex centrally disposed projection on the ends of said drum, a pulley rotatively engaged with said drum, a plurality of rotatable blade-holders disposed around said drum, a pulley of smaller diameter than said first-mentioned pulley on each 30 of said blade-holders, and a reciprocatable flexible band engaging all of said pulleys. 35

ALFRED WILLIAM SMITH.
